UNITED STATES PATENT OFFICE.

ROBERT MOÏSE BENOIT AARONSON, OF PARIS, FRANCE.

BOTTLE-CAP.

1,173,473.

Specification of Letters Patent. Patented Feb. 29, 1916.

Application filed May 26, 1913. Serial No. 770,008.

To all whom it may concern:

Be it known that I, ROBERT MOÏSE BENOIT AARONSON, a citizen of the French Republic, residing at Paris, in France, have invented 5 certain new and useful Improvements in Bottle-Caps, of which the following is a specification, reference being had therein to the accompanying drawing.

This invention has reference to an 10 proved bottle cap to be applied to any kind of receptacles whatsoever, such as bottles, jars, pots and the like, so as to permit of unstoppering the receptacle by hand without the assistance of any tool or instrument and 15 of restopping it hermetically with the same facility after extracting a portion of its contents.

I shall now describe my invention with reference to the accompanying drawing 20 showing one form of construction by way of example, in which:

Figure 1 shows separately the various parts composing the cap. A is a metal capsule, the borders of which are threaded so as 25 to screw on to C. B is a washer contained in the capsule A. C is the metal socket threaded at its upper portion for receiving the capsule A. D is a split ring of square metal wire. E is a sealing band for assuring 30 the inviolability of the contents of the receptacle to which the system is applied. Fig. 2 shows in section one method of fitting the system to a special bottle with a circular groove on the upper portion of the neck. Fig. 3 shows another method of fastening the system to an ordinary bottle, that 35 is to say without groove, by means of the split ring D provided for this purpose. Fig. 4 is a top plan view of the sealing band.

40 This system of stoppering is employed in the following manner: Before stoppering the receptacle the capsule A with the washer B is screwed to the threaded portion of the socket C so as to form one piece, then by 45 means of a special machine the socket is firmly fitted to the neck G of the receptacle by means of its lower portion by pressing the metal into the groove H provided for this purpose in the receptacle specially constructed for fitting with this stoppering system such as shown in Fig. 2; or by means 50 of a metal ring or binding compressing the socket against the walls of the receptacle or otherwise. Fig. 2 also shows the special 55 form of neck G of the bottle with its circular groove H.

For ordinary bottles (Fig. 3), that is to say those that have not been constructed specially and consequently are not provided with a groove, a split ring of square metal wire is employed which is placed on the neck of a bottle and which, owing to its elasticity permits of an expansion and is pushed down until it has passed over the customary outer rim on the bottle neck forming a more or less 60 pronounced projection, whereafter the split rim reassumes its original form and as its interior diameter is slightly smaller than the outer diameter of the neck at the part where it is situated, the ring will contract around 65 the bottle neck underneath of said rim and thus firmly be positioned around the bottle neck. The ring D thus arranged on the neck of the bottle is for the purpose of offering a sufficient and regular projection so as to 70 be able to tighten up on it the lower portion of the socket C which could not be done otherwise on account of the irregularity of the bottles which are not specially constructed. 75

80 In order to guarantee the contents of the receptacle a sealing band E which is removed by tearing and made of metal or goldbeater skin or other suitable material is placed on the capsule A in a diametral 85 direction. Furthermore its two ends are folded under the lower edge of the socket, so that this sealing band is held by the clamping of the stoppering system on the receptacle (see plan, Fig. 4). This band has two 90 notches F (one on each edge) slightly passing beyond the axis X so as to form a weak point which permits of it being torn when desired. 95

The system if applied to bottles, jars, pots or the like by one of the means referred to above, it is evident that for unstoppering the receptacle in order to extract a portion of its contents no special instrument will be necessary. It suffices to unscrew the capsule A 100 which carries with it the washer B, this unscrewing movement exerting a traction effort on the band E which is broken at the notches F and which after being completely torn permits of wholly withdrawing the capsule 105 A. In order to restopper the receptacle after use for the purpose of preserving its contents in good condition by excluding the surrounding air, the above operation is reversed, that is to say the capsule A is 110 screwed back on the socket C, the washer B again presses on the neck of the receptacle

which it hermetically closes. These two operations are repeated as often as desired, as long as the receptacle is not empty. By means of this system the contents do not deteriorate or alter and if for example the bottle contains mineral water or beer the liquids retain their gases up to the end.

The threading of the capsule and that of the socket may be substituted by any other 10 fastening system such as for example a bayonet joint.

Having now described my invention and set forth its merits, what I claim, and desire to secure by Letters Patent is:

15 An improved stopper for bottles, jars

and the like comprising in combination, a screw threaded cap containing a washer, a sealing band of metal provided with two notches on each border passing beyond the longitudinal axis of the band, and adapted 20 to be automatically torn when the cap is unscrewed for unstopping the receptacle, substantially as described.

In testimony whereof I affix my signature in presence of two witnesses.

ROBERT MOISE BENOIT AARONSON.
